UNITED STATES PATENT OFFICE.

JEAN VÖLKER, OF NEU-ISENBURG, NEAR FRANKFORT-ON-THE-MAIN, GERMANY, ASSIGNOR TO THE FIRM OF PETER WEIL & CO., OF RODELHEIM, NEAR FRANKFORT-ON-THE-MAIN, GERMANY.

TYPE-WRITER.

No. 856,377.

Specification of Letters Patent.

Patented June 11, 1907.

Application filed February 12, 1906. Serial No. 300,676.

To all whom it may concern:

Be it known that I, JEAN VÖLKER, a subject of the German Emperor, and a resident of Neu-Isenburg, Germany, have invented 5 certain new and useful Improvements in or Relating to Type-Writers, of which the following is a specification.

This invention relates to an improved arrangement which will enable the position of 10 the carriage to be adjusted in a direction at right angles to the track so as to compensate for the thickness of variable numbers of copies to be typed and insure a uniformly straight blow of the type on the paper.

15 For the purpose of obtaining faultless typing and causing the type to strike the paper perfectly square and with a uniform blow, it is absolutely necessary with most typewriting machines and more particularly 20 those in which the type strikes from the front of the sheet placed over the roller, to provide for an invariable stroke of the type levers. However, most of the type lever mechanisms have a well defined stroke, so 25 that when an unusually thick layer of paper *i. e.* a large number of copies are placed in the machine it will be necessary to shift the paper away for an appropriate distance. This rearward adjustment of the paper in 30 machines having a front action of the type-levers is effected according to the invention by a receding motion of the carriage and paper-roller by the special means illustrated in the accompanying drawings, in which:—

35 Figure 1 is a side elevation of the carriage of a typewriter fitted with means for adjusting the position of the carriage to suit the amount of paper on the roller. Fig. 2 shows a rear view of the carriage. Fig. 3 is a plan 40 view of Fig. 2.

The carriage *h* which holds the paper roller in the usual manner, runs on rails *l* and *f* respectively. The front rail *l* has a straight top-surface upon which the carriage wheel *k* runs. This rail is immovable and only the 45 carriage wheels alter their track along each rail at the forward, or rearward, adjustment of the carriage in accordance with the amount of paper on the roller. The adjustment of 50 the carriage in the direction at right angles to the track is effected through the intervention of the rear rail *f* which for this purpose is carried on pivoted arms *b* secured to each end of the machine by bolts *a* or the like.

The arms *b* are formed with a slot *e* for the reception of an eccentric stud *d* mounted on the end of a crank lever *c*. A scale *s* is provided on the side of the machine from which the number of sheets and the corresponding position of the carriage can be ascertained. 55

The rail *f* is of U-shaped cross-section which allows the carriage wheels *i* to travel along the inner path thereof while horizontal wheels *m* of appropriate diameter are provided to run between the sides of such rail and prevent the carriage from unintentional forward or rearward motion. To the rear end at the middle of the carriage is attached a depending arm having a forwardly projecting portion *g* which takes beneath the rail *f* to prevent the tilting of the carriage as will be understood from Fig. 1. If desired, a similar device may be provided at the front of the carriage by adapting an arm to engage around a convenient recess or the like in the machine- 75 frame.

Obviously the arrangement hereinbefore described permits of the ready adjustment of the carriage *h* to suit the amount of paper on the roller and thus insures the types coming square upon the paper on the roller as is indicated by the arrow *p*. In typewriters having a different lever motion the details of construction of the parts can be altered to 80 suit each machine. 85

Having now fully described my said invention, what I claim and desire to secure by Letters Patent is:

1. In a typewriter the combination with the carriage and the platen of a flat front rail adapted to receive the front wheel of the carriage and to allow of the latter running in parallel paths on it, of an U-shaped rear rail, of vertical wheels mounted on the carriage and adapted to run on the rear rail, of horizontal guide rollers mounted on vertical studs of the said carriage and adapted to move in the channel of the said guide rail and means for imparting and controlling forward or rearward adjustment of the carriage, substantially as and for the purpose described. 90

2. In a typewriter the combination with the carriage and the platen of a flat front rail adapted to receive the front wheel of the carriage and to allow of the latter running in parallel paths on it, of an U-shaped rear rail, of vertical wheels mounted on the car- 100 105

- riage and adapted to run on the rear rail, of horizontal guide rollers mounted on vertical studs of the said carriage and adapted to move in the channel of the said guide rail, of 5 arms pivoted to the frame work of the machine and supporting the said guide rail and means for causing the said arms to swing on the frame work and for adjusting same substantially as and for the purpose set forth.
- 10 3. In a typewriter the combination with the carriage, the front rail and the rear guide rail of the latter, the swinging arms supporting the said guide rail, of a slot arranged in one of the said arms, an eccentric stud working in the said slot and a crank handle adapted to operate the said stud substantially as and for the purpose set forth.
- 15 4. In a typewriter the combination with the carriage, the front rail and the rear guide rail of the latter, the swinging arms supporting the said guide rail, of a slot arranged in one of the said arms, an eccentric stud working in the said slot and a crank handle adapted to operate the said stud substantially as and for the purpose set forth.

4. In a typewriter the combination with the carriage, the front rail and the rear guide rail of the latter, the swinging arms supporting the said guide rail, of a slot arranged in one of the said arms, an eccentric stud working in the said slot and a crank handle adapted to operate the said stud, of a scale mounted on the frame work of the machine under 20 the said operating arm substantially as and for the purpose set forth.

In testimony whereof I have hereunto set my hand in presence of two witnesses.

JEAN VÖLKER.
